B. M. SCHWEIZER

COMB

Filed April 15, 1925

B. M. Schweizer Inventor

By *C. Snow & Co.* Attorneys.

UNITED STATES PATENT OFFICE.

BERNARD MARX SCHWEIZER, OF NASHVILLE, TENNESSEE.

COMB.

Application filed April 15, 1925. Serial No. 23,346.

To all whom it may concern:

Be it known that I, BERNARD M. SCHWEIZER, a citizen of the United States, residing at Nashville, in the county of Davidson and State of Tennessee, have invented a new and useful Comb, of which the following is a specification.

This invention relates to toilet articles and more particularly to dressing combs.

10 The object of the invention is to provide a comb of this character so constructed that it may be quickly and thoroughly cleaned thereby insuring a comb sanitary at all times.

15 Another object is to provide a comb having the back so constructed that one member thereof may be removed to permit a jet of water to be forced between the teeth at their junction with the back and thus quickly remove all deposits of oil, dirt and the like which collect between the top of the teeth and the comb back or body.

20 With the foregoing and other objects in view which will appear as the description proceeds, the invention resides in the combination and arrangement of parts and in the details of construction hereinafter described and claimed, it being understood that changes in the precise embodiment of the 25 invention herein disclosed may be made within the scope of what is claimed without departing from the spirit of the invention.

In the accompanying drawings:—

30 Figure 1 represents a side elevation with parts broken out of a comb constructed in accordance with this invention;

Fig. 2 is a top plan view thereof with parts broken out;

Fig. 3 is a transverse section taken on the 35 line 3—3 of Fig. 1;

Fig. 4 is a detail side elevation showing a slight modification; and

Fig. 5 is a transverse section taken on the 40 line 5—5 of Fig. 4.

45 The comb 1 embodying this invention is equipped with a hollow back 2, the chamber 3 formed therein being wedge-shaped in cross section with the walls thereof tapering inwardly, said chamber extending down into the teeth 4.

A removable wedge-shaped section 5 is designed to be normally mounted in the

chamber 3 and is preferably of a width greater than the depth of the chamber with its upper edge projecting above the upper edge 55 of the back as is shown clearly in Figs. 1 and 3. The tapered lower edge 6 of section 5 also preferably extends down into the teeth 4 which are recessed at their upper end as shown at 7, said recesses communicating 60 with chamber 3.

The section 5 is preferably made slightly longer than the comb back 2 and is provided at its ends with inwardly extending curved fingers 8 which fit down over the ends of the 65 comb back and facilitate the removal and insertion of section 5.

Should the back 2 and section 5 be made of metal the section will be held in its seat by friction. Should these parts however be 70 made of celluloid, ivory or similar substance it will be necessary to provide auxiliary fastening means for holding the section 5 in position. In Figs. 4 and 5 small inset screws 9 are shown for this purpose which extend transversely through the comb back and the removable section.

In the use of this comb when it is desired to clean it section 5 is removed and a jet of water is forcibly entered through 80 chamber 3 and flowing down between and against the teeth 4 thoroughly cleanses them of all grease, dust and the like which may have collected on them.

After the comb has been cleaned the section 85 5 is replaced and operates to reinforce the back of the comb preventing all possibility of its breaking.

I claim:—

1. A comb of the class described having 90 a back provided with a chamber communicating with the space between the teeth, and a removable member in said chamber to normally close it and reinforce the back.

2. A comb of the class described having 95 a back provided with a chamber communicating with the space between the teeth, and a removable member in said chamber to normally close it and reinforce the back, said member having curved fingers at its ends to 100 fit over the ends of the comb back to facilitate its removal and insertion and to assist in retaining it in operative position.

3. A comb of the class described having

a back provided with a chamber opening between the teeth thereof and through the upper edge of the back, the walls of said chamber converging inwardly, a removable wedge-shaped member insertible in said chamber and snugly engaging the walls thereof, said member being removable to permit cleans-

ing water to be entered through the chamber and which operates as a reinforce for the back when inserted in the chamber. 10

In testimony that I claim the foregoing as my own, I have hereto affixed my signature.

BERNARD MARX SCHWEIZER.
